UNITED STATES PATENT OFFICE.

ADOLPHUS M. SHENK, ANDREW SALTZER, AND LOUIS SALTZER, OF CALEXICO, CALIFORNIA; SAID ANDREW SALTZER AND SAID LOUIS SALTZER ASSIGNORS OF ONE-SIXTH TO SAID SHENK.

WRENCH.

1,408,143.

Specification of Letters Patent. Patented Feb. 28, 1922.

Application filed January 3, 1921. Serial No. 434,698.

To all whom it may concern:

Be it known that we, ADOLPHUS M. SHENK, ANDREW SALTZER, and LOUIS SALTZER, citizens of the United States, residing at Calexico, in the county of Imperial and State of California, have invented new and useful Improvements in Wrenches, of which the following is a specification.

Our invention relates to new and useful improvements in wrenches of the type having one jaw that is movable in order that it may be adjusted toward and away from the other or fixed jaw, the principal objects of our invention being to provide a relatively simple, strong and durable wrench, the construction of which enables it to be easily, and cheaply produced; further, to provide a wrench having a movable jaw that can be easily and quickly adjusted toward and away from the fixed jaw, said movable or adjustable jaw being provided with means which very effectively lock it to the shank or body of the wrench when adjusted to the desired position.

With the foregoing and other objects in view, our invention consists in certain novel features of construction and arrangement of parts that will be hereinafter more fully described and claimed, and illustrated in the accompanying drawings in which:

Fig. 1 is a side elevational view of a wrench constructed in accordance with our invention.

Fig. 2 is a front elevational view of the wrench with the handle broken away.

Fig. 3 is a vertical section taken approximately on the line 3—3 of Fig. 2.

Fig. 4 is a perspective view of a part of the shank or body of the wrench and with the adjustable jaw positioned thereupon.

Referring by numerals to the accompanying drawings which illustrate a practical embodiment of our invention, 10 designates the main body or shank of the wrench, 45 the same being formed of a substantially straight bar of metal, the lower end thereof being formed into a handle 11, and the upper end having formed thereon a laterally projecting jaw 12, the under face of 50 which is toothed or corrugated, as designated by 13.

One edge of the body or shank 10 is provided with transversely disposed teeth 14, and arranged to slide freely upon this

toothed portion of the shank is a sleeve 55 15, preferably a metal tube that is substantially square or rectangular in cross section.

Formed integral with the upper end of this sleeve is a laterally projecting jaw 16, 60 the upper face of which is toothed or corrugated, as designated by 17.

Portions of the side walls of sleeve 15 project beneath the jaw 16 to form ears 18, and seated therein is a transversely disposed 65 pin or rivet 19 upon which is pivotally mounted a dog 20 in the form of a metal block, the inner face of which is provided with transversely disposed teeth 21 that are adapted to engage the teeth 14 on shank 10. 70

Seated in the under side of jaw 16 is one end of a bow spring 22, the same extending downwardly and inwardly against the curved outer face of dog 20, and the lower end of said bow spring is connected in any 75 suitable manner to a transversely disposed pin or rivet 23, which latter is positioned just beneath the dog or block 20.

Bow spring 22 is connected at a point intermediate its ends to the dog or block 20 80 in any suitable manner, preferably by means of a rivet such as 24. The upper end of a flat spring 25 is pivotally connected to the pin or rivet 23, and the lower end of said flat spring is fixed in any suitable manner 85 to the lower portion of the adjacent face of sleeve 15.

Projecting outwardly from the lower portion of sleeve 15, and below the point where springs 22 and 25 are connected, are ears 90 26, in which is seated a transversely disposed pin 27, and fulcrumed thereupon is a relatively short lever 28, the upper end of which is provided with notched ears 29 that receive the ends of pin 23. 95

The outer face of the lower portion of lever 28 is knurled or corrugated as designated by 30, in order that it may be firmly engaged by the thumb or finger when the movable jaw is being shifted toward or 100 away from the fixed jaw.

Under normal conditions the bow spring 22 and flat spring 25 cooperate to exert inward pressure upon the lower portion of dog 20, thereby retaining the teeth 21 on 105 said dog in engagement with certain of the teeth 14 on shank 10, and, with the parts so positioned, the wrench can be used in

the ordinary manner for manipulating a nut or for turning or holding a pipe or small piece of work.

To adjust the jaw 16 toward or away from fixed jaw 12, it is only necessary to place the thumb or finger on the corrugated lower face of lever 28 and exert sufficient pressure to swing said lever on its fulcrum and move pin 23 outwardly, which action necessarily flexes the springs 22 and 25, and by such operation the dog 20 is swung upon its axis so that the teeth 21 are disengaged from the teeth 14, and the sleeve 15 and parts carried thereby are now free to be moved lengthwise upon shank 10.

Obviously when the pressure upon the lower end of lever 28 is removed, the co-operating springs will actuate dog 20 so that the teeth thereof are engaged with the teeth on shank 10, with the result that the sliding jaw is locked to said shank in its adjustable position.

A wrench of our improved construction is comparatively simple, is "quick acting", in that the movable jaw can be instantly adjusted toward or away from the fixed jaw, and said wrench is adapted for a wide variety of uses.

Various changes in the size, form and construction of the various parts of our improved wrench may be made and substituted for those herein shown and described, without departing from the spirit of our invention, the scope of which is set forth in the appended claims.

We claim as our invention:

1. A wrench having a shank and a fixed jaw, a jaw mounted on the shank for movement toward or away from the fixed jaw,

a dog associated with the movable jaw for locking the same to the shank, a pair of springs co-operatively operating against said dog for retaining said dog in engagement with said shank, and a member connected to said springs for flexing said springs and effecting the disengagement of the dog from said shank.

2. A wrench comprising a shank having a handle on one end and a fixed jaw on the other end and having transversely disposed teeth intermediate of its ends, a sleeve sliding freely upon the toothed portion of the shank, a movable jaw upon one end of the sleeve in opposition to the fixed jaw, ears extending from the sleeve on opposite sides of the teeth of the shank and from the movable jaw, a dog mounted between the ears and having teeth for engaging the teeth of the shank, a pin holding the dog in position, a spring having one end seated in the movable jaw and engaging the dog, a rivet in the free end of the spring, means for connecting the spring to the dog, a second spring connected to the rivet and to the sleeve, ears extending from the sleeve past the sides of the second spring, and a lever pivotally connected to the ears and engaging the rivet connecting the two springs, there being a handle upon the opposite end of the lever from the rivet so that by pressing the handle the dog is released from the shank and by releasing the handle the springs press the dog against the shank.

In testimony whereof we have signed our names to this specification.

ADOLPHUS M. SHENK.

ANDREW SALTZER.

LOUIS SALTZER.
